(57) **CLAIM**

The ornamental design for a surface configuration of a center console for a vehicle, as shown and described.

DESCRIPTION

This application is related to the following co-pending applications, of the inventors, filed on even date herewith: Application Ser. No. 29/162,833, entitled "Surface Configuration of a Dashboard for a Vehicle"; Application Ser. No. 29/162,831, entitled "Surface Configuration of a Center Console for a Vehicle"; and Application Ser. No. 29/162,832, entitled "Surface Configuration of a Control Panel for a Vehicle".

FIG. 1 is a top view of a surface configuration of a center console for a vehicle according to our novel design; and, FIG. 2 is a left side view of the surface configuration of a center console for a vehicle according to our novel design, the right side view being mirror symmetrical.

The dash lines included depict environment and are not part of the claimed design.
